UNITED STATES PATENT OFFICE.

JOHN T. LYNCH, OF ROCHESTER, NEW YORK.

TRUCK.

1,423,234.

Specification of Letters Patent. Patented July 18, 1922.

Application filed July 24, 1920. Serial No. 393,794.

To all whom it may concern:

Be it known that I, JOHN T. LYNCH, a citizen of the United States, residing at Rochester, in the county of Monroe and 5 State of New York, have invented certain new and useful Improvements in Trucks; and I do hereby declare the following to be a full, clear, and exact description of the same, reference being had to the accompanying drawings, forming a part of the specification, and to the reference numerals marked thereon.

My present invention relates to trucks and especially to hand trucks of the type usually 15 employing a heel permitting them to be adjusted beneath the object to be carried and the latter thereby raised to loaded position through manipulation of the truck itself, and the invention has for its object to provide a simple, light and serviceable truck of this nature that will be particularly easy 20 to load and unload, that will accommodate securely objects of different shapes and sizes, and which may be operated with facility and 25 safety over difficult ground such as steps, embankments, etc. To these and other ends the invention consists in certain improvements and combinations of parts, all as will be hereinafter more fully described, the 30 novel features being pointed out in the claims at the end of the specification.

In the drawings:

Figure 1 represents a side view of my truck in position for loading a container.

35 Figure 2 is a side view similar to Figure 1 showing the container in one carrying position.

Figure 3 is a side view of the truck showing the container in another position for 40 carrying.

Figure 4 is a top plan view of my truck with the load removed.

Figure 5 is a section on the line 5^a—5^a of Figure 4.

45 In the present embodiment of my invention I have shown a truck specifically adapted and designed for removing ash and refuse barrels and containers from dwellings and conveying them to the street to be loaded 50 into wagons, a service constantly in demand and commonly supplied by municipal authorities. This work must be carried on in all seasons under snow and other conditions, the receptacles provided by the individual householders may vary greatly in 55 size, shape and capacity, and they must be

transported up and down steps and over difficult ground without spilling. My invention offers improvements adapted to meet these conditions, and referring to the drawings the numeral 1 indicates the frame or bed of my truck which may be of any desired form or shape provided at one end with the heel piece 2 for loading and retaining the load in position. At the other 65 end of the frame are provided handles 3 which may be of any desired shape or form and are, for purposes of illustration, shown as extending upwardly somewhat above the bed of the truck. To prevent sinking in 70 soft ground the main supporting wheels 4 are provided with wide rims or tires, and for facility in going up and down stairs these wheels are made relatively large in diameter. Some usual and convenient form 75 of axle 5 is provided for mounting the wheels preferably arranged back from the heel piece 2 so as to be beneath the center of gravity of a load of average size. The frame or bed of the truck comprises side 80 bars 6 between which are connected the carrying straps 7 slightly curved downwardly as is common to accommodate loads of different shapes or sizes. In order to enable the truck to be used on walks or paths 85 which are narrower than the distance between the two main wheels, and in order to facilitate moving the loads up and down stairs or over bumps, the relatively small pilot wheel 8 is adjustably mounted beneath 90 the frame and behind the main wheels. For purposes of adjusting the pilot wheel to and from the frame and the side wheels, its foreframe 9 is pivotally attached at 10 to the underslung main wheel axle 5. The rear 95 supporting member 11 of the pilot wheel is adjustably connected with the cross bar 12 by means of a plurality of perforations 22 arranged in the member 11 for selective co-operation with the pin 23. Thus it will be 100 seen that by moving the pin 23 in the cross member 12 in the different perforations 22 of the member 11 the pilot wheel will be raised or lowered from the ground about the pivot 10.

105 Pivots secured to the member 12 is the arm 13 provided at its outer end with the downwardly extending prongs or hooks 15 and 16 which are arranged one in front of the other longitudinally of the truck. 110 Although the hooks have been described as being one in front of the other it will be

understood that one of them may be placed at the side but still ahead of the other. Adjustably secured to the arm of 13 for movement along the same is the depending hook or prong 17 which is adapted for cooperation with the tops of various sizes of loads to retain the same on the truck as shown in Figure 3. A similar sort of adjustable hook or prong 18 is also movable along the arm 13 for purposes of retaining a second load in position should such be carried by the arm 13 as shown in Figure 2. These hooks 17 and 18 may be adjustably secured in any well known manner but for purposes of illustration I have shown them as being provided with the usual wing nut and clamping screw 19. In order to more firmly support the arm 13 about its pivot its adjacent end 14 is preferably bifurcated or otherwise widened to form a two point attachment to the cross bar 12 so as to lessen the tendency to any sidewise flexure. The load to be carried by the truck has been illustrated in the form of a cylindrical container or barrel 20 but it will be understood that other forms of loads or containers are adapted to be carried by this truck. The widened end 14 of the arm 13 affords an appropriate rest for another or smaller container 21 which, as shown in Figure 2, may be positioned on the arm 13 between the handles 3 and adjustable prong 18. Secured by rivets 25 to the cross bar 12 is the supporting member 24 for the rear supporting member 11 of the pilot wheel as is illustrated in Figure 5.

Among the advantages of my device may be stated that the truck is adapted to load and unload containers without the necessity for lifting one edge or the entire body of the container or barrel directly by hand as is usual. From Figure 1 it will be seen that when the truck is wheeled up against the barrel to be loaded, the arm 13 may be moved down so that the upper edge of the barrel engages between the prongs 15 and 16 thus enabling the arm 13 to be pushed to tilt the barrel when, after one edge thereof is raised, the heel piece 2 may be inserted beneath the raised edge. If desired the handles may be then lowered and the barrel carried in the position shown in Figure 2 by means of the heel piece and prongs 15 and 16 of the arm 13. If it is desired to carry the load in the manner indicated by Figure 3 the barrel 20 may be loaded in the conventional way, or it may be brought to this position from the position indicated in Figure 2 by lowering the handles, disengaging the arm 13 from the top of the barrel and allowing the same to fall back upon the carrying straps 7. Attention is directed to the fact that when large wheels with wide rims are selected, soft ground and steps may be transversed with greater facility. When two loads are

carried as shown in Figure 2 it will be apparent that the wheels are substantially midway between these loads. Thus a good distribution of weight is secured at all times. whether the load be in the position shown in Figure 3 or in the position shown in Figure 2. The use of an adjustably mounted pilot wheel 8 helps movement of the truck over bumps and along a path of less width than the distance between the main wheels. Probably the most noteworthy advantage of my truck is the ease of loading and unloading.

The pilot wheel and its mounting is an additional advantage in going up and down steps, when the same may be used as a pivot and lever. By having the handles extend or curved upwardly as shown a rest or abutment is formed for holding the second container in place on the pivot arm.

I claim as my invention:

1. The combination with a frame of a heel piece at one end thereof and an operating handle at the other end, a hook arm provided with a plurality of prongs and pivotally secured to the frame, said hook being adapted to engage the upper edge of an object constituting the load between said prongs for retaining the same on the outer edge of the heel piece, and an upwardly extending prong adjustable along the hook arm to fit different sizes of loads which may be carried upon said arm between the operating handle and the last mentioned prong.

2. The combination with a frame of an operating handle therefor, a heel piece at one end of said frame adapted to support an article, a pivotal hook arm secured to the frame adjacent the operating handle to maintain said article upright and adapted to itself support an additional article, and a pair of supporting wheels of relatively large diameter located substantially midway between the point of attachment of the hook arm and the heel piece and adapted to assume a position below and between the two articles carried when both are in upright positions.

3. In a truck the combination with a frame of an operating handle therefor at one end of the frame, a relatively large supporting wheel and axle by which said frame is carried, a smaller pilot wheel secured beneath the frame and between the larger wheel and the handle and having a supporting member pivoted to the axle, and means for adjusting the pilot wheel on its pivot to regulate the height of the pilot wheel from the frame and axle of the larger wheel.

4. In a truck, the combination with a frame provided with an axle and main wheels and with an operating handle at one end, of a pilot wheel located between the axle and handle and having a pivoted supporting arm and an adjusting arm connected

- to the pilot wheel and cooperating with the frame to swing it on its pivot and regulate its distance from the frame.
5. In a truck, the combination with a frame provided with a yoke shaped underslung axle and main wheels thereon and with an operating handle at one end, of a pilot wheel located between the axle and handle and having a yoke shaped supporting arm pivoted to the yoke of the axle, and means for adjusting the supporting arm on its pivot to regulate the distance between the pilot wheel and frame.
- 10 6. In a hand truck, the combination with a pair of ground wheels and a frame pivoted thereon and having a heel at its lower end adapted to engage beneath the edge of a barrel at a point well forward of the wheel and to lift the barrel, of a yoke arm connected to the frame above the wheel pivots
- 15 and adapted at its outer end to cooperate with the upper portion of the barrel to hold it upright and against tilting when raised by the heel, the inner arm being yoke shaped to support an additional load, and retaining means for holding an additional load on the yoke arm.
- 20 7. In a hand truck, the combination with a frame having a heel at its lower end adapted to engage beneath the edge of a barrel and a handle portion at its upper end, of means connected to the frame and adapted to cooperate with the upper portion of the barrel to hold it upright and against tilting when raised by the heel, said means itself constituting a carrier for another object and being provided with means for confining such other object between itself and the handle portion.

JOHN T. LYNCH.
